THE NORRIS PETERS CO., PHOTO-LITHO., WASHINGTON, D. C.

UNITED STATES PATENT OFFICE.

LEROY STONER, OF CENTREVIEW, MISSOURI.

ROTARY ENGINE.

SPECIFICATION forming part of Letters Patent No. 599,648, dated February 22, 1898.

Application filed June 18, 1897. Serial No. 641,345. (No model.)

To all whom it may concern:

Be it known that I, LEROY STONER, of the city of Centrevue, Johnson county, State of Missouri, have invented certain new and useful Improvements in Rotary Engines, of which the following is a full, clear, and exact description, reference being had to the accompanying drawings, forming a part hereof.

My invention relates to compound steam-engines; and it consists of the novel construction, combination, and arrangement of parts hereinafter shown, described, and claimed.

Figure 1 is a top plan view of a compound rotary steam-engine constructed in accordance with the principles of my invention. Fig. 2 is an end view of the engine shown in Fig. 1, looking in the direction indicated by the arrow. Fig. 3 is a transverse sectional view taken approximately on the line 3 3 of Fig. 1. Fig. 4 is a horizontal section taken approximately on the line 4 4 of Fig. 3. Fig. 5 is a transverse section taken approximately on the line 5 5 of Fig. 4 and looking in the direction indicated by the arrow. Fig. 6 is a vertical longitudinal section taken approximately on the line 6 6 of Fig. 3. Fig. 7 is a diagrammatic view of the plate, equal to a section taken on the line 7 7 of Fig. 6 and looking in the direction indicated by the arrow, all the parts except the plate being removed. Fig. 8 is a view analogous to Fig. 7 and taken on the line 8 8 of Fig. 6. Fig. 9 is a side elevation of one of the rotary slide-valves. Fig. 10 is a diagrammatic view illustrating the arrangement of the pistons upon the piston-shaft. Fig. 11 is a diagrammatic view illustrating a modification.

My object is to construct a compound rotary steam-engine of the type employing overlapping chambers and cog-wheel pistons.

Referring by numerals to the drawings, the engine rests upon the base-plate 20, mounted in a horizontal position and having the flange 21, projecting downwardly and forming the means of holding the plate elevated from the foundation, said flange 21 extending entirely around the edge of the plate. The flange 21 is reinforced by the longitudinally-extending walls 22, extending downwardly from the plate 20 equal distances apart and equal distances from the portions of the flange.

The engine consists of four steam-cylinders

23, 24, 25, and 26. Each of the steam-cylinders consists of two overlapping cylindrical chambers 27 and 28, as shown in Fig. 3. The steam-chambers are arranged in longitudinal alinement, as shown in Fig. 6. The piston-shaft 29 extends from end to end of the engine and is located at the axial center of the chamber 27. The piston-shaft 30 extends from end to end of the engine and is located at the axial center of the chamber 28. The steam-chambers 27 and 28 are formed by the castings 31 and 32. The castings are substantially alike and are attached together by the bolts 33, inserted through the flange 34 in such a way that the steam-cylinders may be divided on a horizontal line by removing the bolts 33. A flange 35 projects outwardly from one end of each of the castings 32, and a similar flange projects outwardly from the castings 31 in alinement with the flange 35, and a flange 36 projects outwardly from the opposite end of the castings 32, and a similar flange projects outwardly from the opposite end of the castings 31 in alinement with said flange 36.

A cylinder-head 37 is placed against the front end of the cylinder 23 and is secured in position by means of the bolts 38, inserted through the flange 36 and through the cylinder-head. A cog-wheel piston 39 is placed upon the shaft 29, and a similar cog-wheel piston 40 is placed upon the shaft 30, the cogs of said pistons intermeshing, as shown in Fig. 3. The steam-ports 41 and 42 are formed vertically through the castings 32 and 31, respectively, in vertical alinement with each other and on a vertical line substantially half-way between the piston-shafts 29 and 30, the ports being formed only in the castings composing the cylinders 23 and 26.

The cylinder-head 43 is placed against the rear end of the cylinder 23, and said cylinder-head is constructed as shown in Fig. 7. The opening 44 is a bearing for the piston-shaft 29, and an opening 45 forms a bearing for the piston-shaft 30. The openings 46, 47, 48, and 49 are exhaust-ports for the waste steam and the openings 50, 51, 52, 53, 54, 55, 56, and 57 are exhaust-ports for live steam—that is, the steam to be used in compounding.

The rotary slide-valve 58 is placed upon the piston-shaft 29 against the rear face of

the cylinder-head 43 and the rotary slide-valve 59 is placed upon the piston-shaft 30 against the rear face of the cylinder-head 43, and the peripheries of said slide-valves 58 and 59 are provided with gear-teeth, said gear-teeth intermeshing. The rotary slide-valves 58 and 59 are substantially alike and are constructed as shown in Fig. 9. An elongated segmental opening 60 is formed through the web of the valve immediately inside of its periphery and extending equal in length to substantially one-fourth of the circumference of the valve, said opening being designed to serve as a passage for the live steam which passes through the exhaust-ports. An oblong opening 61 is formed through the web of the valve a distance from one end of the opening 60 equal to substantially one-fourth of the circumference of the valve, and a similar oblong opening 62 is formed through the web of the valve an equal distance from the opposite end of the opening 60, said openings 61 and 62 being designed to serve as passages for the dead steam which passes through the exhaust-ports.

A cylinder-head 63 is placed against the rear faces of the slide-valves 58 and 59, said cylinder-head being constructed as shown in Fig. 8. The opening 64 serves as a bearing for the piston-shaft 29 and an opening 65 serves as a bearing for the piston-shaft 30. The openings 66, 67, 68, and 69 serve as passages for the live steam which comes through the opening 60 of the slide-valve. The openings 66 and 67 are inclined slightly upwardly and toward each other as they pass backwardly through the cylinder-head and terminate in a single opening upon the rear side of the cylinder-head. The openings 68 and 69 are inclined slightly downwardly and terminate in a single opening upon the rear side of the cylinder-head. The spacing-blocks 70 are placed between the cylinder-heads 43 and 63 outside of the sliding valves 58 and 59, and the bolts 71 are inserted through the cylinder-head 43, then through the blocks 70, and then through the cylinder-head 63, as required to hold said cylinder-heads firmly together, the blocks 70 being of such a size that the slide-valves 58 and 59 are not pinched by tightening the bolts 71.

The castings 31 and 32 are placed against the rear face of the cylinder-head 63, thus forming the cylinder 24. A cylinder-head similar to the cylinder-head 43 is placed against the rear end of the cylinder 24. Then comes another set of the sliding valves 58 and 59. Then comes the cylinder 25, constructed identically like the cylinder 24. Then comes another set of the sliding valves 58 and 59. Then comes the cylinder 26, constructed exactly like the cylinder 23, with the exception that a cylinder-head like 63 is used upon its front end instead of the cylinder-head 37 and a cylinder-head like the head 37 is used upon its rear end instead of the cylinder-head 43. The cylinders 24 and 25 are secured together in the same

way that the cylinders 23 and 24 are secured together, and the cylinders 25 and 26 are also secured together in the same way. The cylinders 23, 24, 25, and 26 are secured to the base-plate 20 by means of the legs 72, attached to said cylinders and to said base.

The belt-pulley 73 is fixed upon the forward end of the piston-shaft 29, and a similar belt-pulley 74 is fixed upon the forward end of the piston-shaft 30. A counter-shaft 75 is mounted above the cylinders and in a line parallel with the piston-shafts 29 and 30, and a double-faced belt-wheel 76 is fixed upon the forward end of said counter-shaft. A straight belt 77 connects the belt-wheel 73 with one of the faces of the belt-wheel 76 and a crossed belt 78 connects the wheel 74 with the other face of the wheel 76.

The piston-shafts 29 and 30 rotate in opposite directions, and the belt 78 is crossed in order that the combined force of said shafts 29 and 30 may be communicated to the counter-shaft 75. A driving-pulley is attached to the rear end of the counter-shaft 75.

All of the cylinder-heads are formed in two pieces and divide upon the same line as the castings 31 and 32, and the bolts 79 are inserted vertically through said cylinder-heads to hold the two pieces together.

The oil-holes 80 are formed downwardly from the upper edges of the cylinder-heads and in positions to lead oil to the piston-shafts. The valve-stem 81 is mounted upon the front side of the engine in a line parallel with the counter-shaft 75 and with the piston-shafts and spur-gears 82 are mounted upon said valve-stem in mesh with the rotary slide-valves 59, as shown in Fig. 5.

Attached to the forward end of the engine is a toothed rack 83, through which the valve-stem 81 extends. The teeth upon the rack 83 are concentric to the valve-stem and describe substantially two-thirds of a circle. A crank-arm 84 is fixed upon the valve-stem immediately in front of the rack 83, and a spring-actuated dog 85 is slidingly connected to said crank-arm in position to engage the teeth of the rack 83. The valve-stem 81 is rotated by manually operating the crank-arm 84 and is held in any desired position by the engagement of the dog 85 with the teeth of the rack 83.

The valve-casing 86 is mounted in transverse alignment with the cylinder 23, with the valve-stem 81 extending through it, and a similar casing 87 is mounted in transverse alignment with the cylinder 26, with the valve-stem 81 extending through it. The valve-casings 86 and 87 are substantially alike and are constructed as shown in Fig. 3.

The rotary valve 88 is fixed upon the valve-stem 81 within the valve-casing, and an opening 89 is formed in one side of the valve 88.

The steam-pipe 90 leads to the T-joint 91, and one branch, 92, of said pipe 90 leads to the top of the valve-casing, while the other branch, 93, leads to one side of the valve-cas-

ing. A pipe 94 leads from the valve-casing to the port 41, and a similar pipe 95 leads from the valve-casing to the port 42. When the valve 88 is in the position shown in Fig. 3, the steam is passing through the steam-pipe 90, then through the branch 92, then through the pipe 94, through the steam-cylinder 23, and the pistons are operated in the direction indicated by the arrows. When the valve 88 is in the position shown in Fig. 3, the crank-arm 84 is in the position shown in Fig. 2 and the rotary slide-valves 58 and 59 are in the position shown in Fig. 5. The position of the valve 88 in the valve-casing 87 is such that when the valve in the valve-casing 86 is in the position shown in Fig. 3 the valve in the valve-casing 87 is forming a connection between the pipes 93 and 95. When the steam enters at the top or through the pipe 94, it exhausts through the lower pipe corresponding to the pipe 95, and vice versa. Spring-actuated packing-plates 96 are arranged to operate in the points of the cogs of the pistons 39 and 40.

Referring to Fig. 10, the pistons are arranged windingly upon the piston-shafts, so that there will be no dead-center. When it is desired to reverse the engine, the crank-arm 84 is manually operated to the opposite end of the rack from the position shown in Fig. 2. Then the steam passes through the pipe 93 and then through the valve and through the pipe 95. Assuming that the valves are in the positions shown in Figs. 1, 2, 3, 4, 5, 35 and 6, the dead-steam exhaust-ports 46 and 47 are closed, the live-steam exhaust-ports 56, 57, 50, and 51 are opened, the dead-steam exhaust-ports 48 and 49 are opened, and the live-steam exhaust-ports 52, 53, 54, and 55 are closed. The steam passes through the steam-pipe 90, through the T-joint 91, through the branch pipe 92 into the valve-casing, through the valve 88, and then through the pipe 94 to a point within the cylinder 23, where the chambers 27 and 28 meet, and at the upper side of the cylinder. The expansion-chamber is formed between the cogs of the pistons 39 and 40 and force said cogs apart, thus rotating the pistons in the directions indicated by the arrows in Fig. 3. After the steam has done its work it is confined in a pocket between the points of two adjacent cogs, as in the upper side of piston 40 in Fig. 3, and the steam from this pocket exhausts through the port 50 in the cylinder-head 43, then through the opening 60 in the slide-valve 59, and then through the port 67 to the next cylinder. When the pocket has moved a short distance farther, the steam may pass through the port 51 to the opening 60. The steam - pockets formed between the points of adjacent cogs upon the piston 39 exhausts in the same way through the ports 56 and 57 to the opening 60 in the slide-valve 58, and then through the port 66 to the next cylinder. This is what I call the "live-steam exhaust." The steam pass-

ing through these ports into the next cylinder again expands and exerts a force in that cylinder and then exhausts in the same way to the next cylinder, and so on throughout the series of cylinders until the end is reached, and then the live steam exhausts through the port 41 to the valve-casing 87 and then to a condenser or the open air. The steam carried by the pockets of the pistons which does not exhaust through the ports 50, 51, 56, and 57 is carried around to the lower side of the cylinder, and when the cogs of the pistons approach each other this dead steam is forced to exhaust through the ports 48 and 49, then through the openings 61 and 62, and then through the ports 68 and 69 to the next cylinder. This dead steam is of little consequence and exerts but a slight resistance to the operation of the engine. When the engine is reversed, as before suggested, the slide-valves 58 and 59 assume the position shown in Fig. 9. Then the live steam exhausts through the lower ports 52, 53, 54, and 55 and the dead steam exhausts through the upper ports 46 and 47.

Referring to Fig. 11, the slide-valves are provided with two openings 60, arranged upon opposite sides of the axial center of the valve, and the openings 61 and 62 are omitted, and the ports through the cylinder-heads are arranged accordingly. By this construction only a slight motion of the slide-valves 58 and 59 is necessary to reverse the engine, while in the preferred form described it is necessary that the slide-valves make a half-revolution.

I claim—

1. In a rotary engine, a series of steam-cylinders arranged side by side, in the meeting walls of which are formed suitable ports, and each cylinder having a pair of overlapping steam-chambers, piston-shafts extending through said series of steam-cylinders at the axial center of said steam-chambers, intermeshing cog-wheel pistons mounted upon said piston-shafts, and intermeshing rotating valves located between the meeting walls of the cylinders and provided with suitably-arranged ports, substantially as specified.

2. In a rotary steam-engine, the combination with a series of steam-cylinders mounted side by side, in the meeting walls of which are formed suitable steam-ports, of the rotating intermeshing valves provided with steam-ports arranged to coincide with the first-mentioned steam-ports, and means for operating said valves, substantially as specified.

3. In a rotary engine, a series of steam-cylinders mounted side by side, in the meeting walls of which cylinders are formed suitable steam-ports, piston-shafts extending through said series of steam-cylinders, intermeshing pistons located upon said piston-shafts, intermeshing rotating valves located between the meeting walls of the steam-cylinders, said valves being loosely located upon the piston-

shafts and provided with suitably-arranged steam-ports to coincide with the previously-mentioned steam-ports, a valve-stem arranged for rotation at one side of the steam-cylinders, pinions mounted upon said valve-stem and meshing with one of the rotating valves, and valves carried by the valve-stem for controlling the inlet of steam to the first cylinder,

der and the outlet of steam from the last cylinder, substantially as specified. 10

In testimony whereof I affix my signature in presence of two witnesses.

LEROY STONER.
